TENT

Harold J. Pohl, Washington, and Norman J. Diederich,
New Haven, Mo., assignors to Kellwood Company, St.
Louis, Mo.

Filed June 17, 1971, Ser. No. 154,267

Term of patent 14 years

Int. Cl. D3—03

U.S. Cl. D88—3

FIG.1

FIG. 2

FIG.3

FIG.4

FIG. 5

FIG. 1 is a perspective view of a tent showing our new design;

FIG. 2 is a front elevational view, the left being a mirror image thereof;

FIG. 3 is a right side elevational view, the left being a mirror image thereof;

FIG. 4 is a top plan view thereof;

FIG. 5 is a rear elevational view thereof.

We claim:

The ornamental design for a tent, substantially as shown and described.
